POLE DERRICK

Herman J. Troche, Fairview Village, and James Howard Holan, Rocky River, Ohio, assignors to J. H. Holan Corporation, Cleveland, Ohio, a corporation of Ohio

Application September 13, 1949, Serial No. 115,420

4 Claims. (Cl. 254—139.1)

1

The invention relates to derricks, and particularly to adjustable boom types of derricks mounted on and operated from utility truck bodies and utilized primarily for erecting and servicing the poles of public utility lines such as power, telephone, and telegraph lines.

The objects of the invention are to provide equipment of the character stated which may be conveniently transported on the truck body, which is conveniently raised, adjusted, and lowered without necessarily imposing heavy work on the line workmen, and which provides a wide working angle within which the necessary operations may be carried out.

Also, certain structural improvements forming part of the invention provide automatic locks for the derrick legs in certain positions.

The annexed drawings and the following description set forth in detail certain means illustrating the improvements in pole derricks, such means constituting, however, only one of the various forms in which the principle of the invention may be embodied.

In said annexed drawings:

Figure 1 is a fragmentary side elevation of a utility truck, partially broken away, upon the top of the body of which the improved pole derrick is mounted for transporting, there being shown in dot-and-dash lines an extended position of one of certain telescoping parts of the legs, certain boom and load lines and control means for the operation thereof being also indicated;

Figure 2 is a rear elevation of the elements shown in Figure 1, there also being shown in dot-and-dash lines a shifted position of an auxiliary derrick leg or brace which in this position has been pivotally shifted from its transporting position to a position preliminary to erection of the derrick;

Figure 3 is a side elevation which shows the derrick erected to a vertical position;

Figure 4 is a rear elevation of the elements as shown in Figure 3;

Figure 5 is a view similar to Figure 3 but showing the pole derrick in operating position at a considerable working angle from the vertical plane of the rear of the truck body, automatic locks for securing the derrick legs in vertical position to a fulcrum bar being shown in open position;

Figure 6 is a rear elevation of the elements as shown in Figure 5;

Figure 7 is an elevation, upon an enlarged scale, looking toward the rear of the truck body, of a fragmentary portion of a fulcrum bar and an

2

automatic lock thereto for a swivel bracket mounted upon the main derrick leg, there being however one of these swivel brackets with its automatic lock on each of the derrick main and auxiliary legs;

Figure 8 is a fragmentary longitudinal vertical section, upon a still larger scale than that of Figure 7, and taken in the plane indicated by the line 8—8, Fig. 7, open positions of the automatic lock parts being also shown in dot-and-dash outline;

Figure 9 is a side elevation, upon an increased scale, of the rear of the truck body and the derrick legs in vertical position;

Figure 10 is a rear elevation of the elements as shown in Figure 9, both of Figures 9 and 10 showing a lock for pivotally securing telescoping sections of the main and auxiliary legs to the truck body; and

Figure 11 is a fragmentary vertical longitudinal section, upon an enlarged scale, taken in the plane indicated by the line 11—11, Figure 10, and more clearly showing the lock for the telescoping sections of the legs.

25 Referring to the annexed drawings in which the same elements are illustrated by the same respective numbers in the several views, the improved pole derrick is designed for mounting on, transporting by, and operative from a truck body

30 1. The derrick has only two legs, a main leg 2, and a secondary leg or brace 3 pivoted at one end in bracket 3¹ to and adjacent one end of the main leg 2.

35 2. When the derrick is being transported, it is carried on top of the truck body 1 in the position illustrated in Figure 1 with the secondary leg or brace 3 pulled over adjacent the main leg 2 as shown in full lines in Figure 2. The legs 2 and 3 in this closely adjacent position for transporting purposes are clamped or fastened together in any suitable manner. Preliminary to erecting the derrick the legs 2 and 3 are unclamped and the leg 3 moved over upon its upper pivotal axis into the position shown in dot-and-dash lines in Figure 2.

40 3. The erection, lowering, and operation of the derrick is controlled from a power driven winch 4 equipped with a double drum structure consisting of a fixed drum 5 servicing the boom line

45 5 and a shorter rotatable drum 6 servicing the load line 12. The boom line 7 is threaded from the drum 5 through a guide roller unit 8 to a connector 9 which forms one end of the head connection line 10 fastened at its opposite end to the head 11 of the main leg 2. The load line

12 is threaded from the drum 6 over a sheave 13 mounted on a telescoping extension 14 of the main leg 2 and thence is threaded over a sheave 15 mounted in the head 11 of the main leg 2 and depends therefrom. The free end of the load line 12 is provided with an eye 16 by which, when necessary, it can be attached to a safety hook 17 secured to a swivel bracket 21 mounted on the main leg 2. There is also a telescoping extension 18 for the brace 3. The leg extensions 14 and 18 are pivotally secured to the body 1 when the derrick is in vertical position or in any operating position, as shown in Figures 5 and 9, by means which will be hereinafter described and are particularly shown in Figures 9, 10, and 11. The telescoping extensions 14 and 18 are pulled out when the derrick legs are in the expanded condition illustrated by dot-and-dash lines in Figure 2 and this extension of the telescoping parts 14 and 18 is effected by removing pins 23 shown in Figure 1 and then replacing these pins 23 after the telescoping parts 14 and 18 have been pulled out.

A fulcrum bar 20 is provided which is removably secured adjacent its ends by pins 23' (Figure 10) to side members of the truck 1 and extends across the rear of the truck body and forms a fulcrum over which the derrick may be moved when being erected or lowered. When the derrick is being transported the fulcrum bar 20 can be removed so as to provide space within the truck body for tall transformers, cable reels, or other large elements forming necessary parts of the operating equipment and line accessories.

The aforementioned swivel bracket for the main leg 2 is indicated by the character 21 and a like element for the brace 3 is indicated by the character 22. These swivel brackets 21 and 22 serve to secure the legs 2 and 3 to the fulcrum bar 20.

These swivel brackets 21 and 22 are provided with locks which are automatically closed, as hereinafter described in detail, when the derrick is moved from the position shown in Figure 5 to the position shown in Figure 9 and are also locked whenever the derrick is being erected to vertical position from transporting position or lowered from vertical position to transporting position.

The derrick is raised by the following procedure:

First, the side brace 3 is unclamped from the main leg 2 and its lower end swung over into the position shown in dot-and-dash lines in Figure 2 and the swivel bracket 22 therefor locked to the fulcrum bar 20. The swivel bracket 21 on the main leg 2 is already locked to the fulcrum bar 20.

Then the pins 23 which engage registering holes in the leg extensions 14 and 18 and the legs 2 and 3, respectively, are removed and the telescoping leg extensions 14 and 18 pulled out, as shown in dot-and-dash lines, Figure 1, and the pins 23 replaced.

Then the boom line 7 is rigged from the fixed drum 5 through the guide roller unit 8 to the connector 9 forming the end part of the head connection line 10, as shown in Figure 3.

Then, with the derrick controlled by the boom line 7, the small drum 6 is operated and the load line 12 swings the connected legs 2 and 3 on the fulcrum bar 20 and raises the derrick to the position shown in Figure 3 at the end of which movement the locking devices at the bottom ends of the leg extensions 14 and 18 are manipulated to secure the bottoms of the extensions pivotally to the base of the truck body.

Then the slack is taken up on the boom line 7 by means of the drum 5 and the locks on the swivel brackets 21 and 22 which secure the legs 2 and 3 to the fulcrum bar 20 are manually unlocked and the derrick lowered as desired by the boom line 7.

The derrick is now in operating position, one of which positions is illustrated in Figure 5 and 6.

To lower the derrick, the latter is pulled in by the boom line 7 so that the swivel brackets 21 and 22 engage the fulcrum bar 20 and thus the legs 2 and 3 are automatically locked to the fulcrum bar 20.

Then the eyelet end 16 of the load line 12 is fastened to the safety hook 17 on the main leg 2, and the slack of the load line 12 is checked to an extent to hold the derrick as it tends to swing forwardly over the fulcrum bar 20.

Then the locks at the bottom of the leg extensions 14 and 18 are manually unlocked and the derrick is pulled over the fulcrum bar 20 by the boom line 7 and then is lowered into transporting position on top of the truck body 1 by means of a controlled paying out of the load line 12. The extensions 14 and 18 are then telescoped into the respective legs 2 and 3 and locked by the pins 23. Then the brace 3 is swung over and clamped to the leg 2.

The swivel brackets 21 and 22 which are automatically but removably clampable to the fulcrum bar 20 are each formed with a forwardly-extended U-shaped member having a web 26 and an extended part 25, Figure 5, comprised of side flanges 27, Figures 7 and 8, having front edge formations providing recesses 28 for the accommodation of the fulcrum bar 20. Formed on the inside walls of the side members 27 are rectangular shoulders 29 which are intersected by a pin 30 mounted at its ends in the side members 27. The pin 30 is prevented from displacement by the set screw 31 mounted in one of the shoulders 29. A web member 32 of the U-shaped part 25 is formed with a hole 32¹ which, in a certain position of the body 34 of a certain movable clamp is in alignment with a recess 34¹ formed in said body 34, for instance, the full line position shown in Figure 8. The clamp is an integral member having an end jaw 35 and an arm 36 and is pivotally mounted on the pin 30. When the hole 32¹ and recess 34¹ of the web member 32 and the clamp body 34 respectively are in alignment, a spring pressed plunger 37 mounted in a housing 38 passes through the hole 32¹ and into the recess 34¹ and locks the clamp body 34. The housing 38 depends from the web 32 of the U-shaped part 25. The plunger 37 can be withdrawn from the recess 34¹ against the compression of the spring by means of the finger ring 39.

When the swivel brackets 21 and 22 are not clamped to the fulcrum bar 20, as indicated in Figure 5, i. e., when the pole derrick is being utilized outwardly of the vertical plane indicated by Figure 3, the clamp is in open position illustrated in dot-and-dash lines in Figure 8. However, as the pole derrick legs 2 and 3 move forwardly toward the vertical position shown in Figure 3 the arm 36 encounters the fulcrum bar 20 and is pivotally moved on the pin 30 to the position shown in full lines in Figure 8 when it will be noted the jaw 35 has been moved to clamping engagement with the fulcrum bar 20. During this movement the curved surface 40 of the clamp body 34 rolls on top of the web 32 of the U-shaped clamp part 25. This movement of the clamp body 34 of which the jaw 35 is a part

moves the recess 34¹ in the body 34 into registration with the hole 32¹ of the web member 32 so that the spring causes the plunger 37 to pass into the recess 34¹ whereby to lock the clamp body 34 and hence the jaw 35. Then the derrick can be rocked over the fulcrum bar 20. The clamp is unlocked by withdrawing the plunger 37 through the medium of the ring 39 whenever it is desired to operate the derrick rearwardly of the vertical position shown in Figures 3 and 9.

The means for pivotally securing the leg extensions 14 and 18 to the truck body 1 comprises a bracket for each of the extensions 14 and 18 having two spaced plates 42 projected rearwardly from the bottom of the truck body 1, to the outer face of one of each of which pairs of plates is secured a keeper 50 which extends at its rear end over a circular hole 49 formed in the plate 42. Each of the pairs of plates 42 has aligned holes 49 and rotatably mounted in one of the holes 49 of each of the pairs of plates 42 is a truncated cylindrical member of the formation clearly shown in full lines in Figure 11, having a plane side 51. To this cylindrical member is secured a pin 41 intersecting the aligned holes 49 and having an angular finger end portion 41¹. Whenever the cylindrical member is in the position shown in full lines in Figure 11, the keeper 50 extends over the body of the cylindrical member and prevents the pin 41 which intersects the cylindrical member and both sides of the extension 14 or extension 18 from being misplaced. This is the operating position whereby the derrick can be pivotally moved forwardly or rearwardly upon the lower part of the truck body 1. However, when the operating end 41¹ of the pin 41 is turned in the dot-and-dash position shown in Figure 11, the truncated part 51 of the cylindrical member is turned to a position adjacent the keeper 50 so that the pins 41 can be withdrawn from the extensions 14 and 18 and the extensions thus permitted to swing in between the plates 42 or outwardly therefrom depending upon whether the extensions 14 and 18 are being coupled up or loosened.

For ground support of the truck body 1 adjacently beneath the pole derrick there are provided two jacks 46 each comprising telescoping sections, the jacks 46 being hinged on pivot pins 47 adjacently below the truck body 1. When the pole derrick is being transported, the jacks 46 are fastened in upper position adjacently below the truck body 1 by chains 48, Figure 1.

What we claim is:

1. In a device of the character described, the combination with a vehicle body having rearwardly projecting ears and pintles removably mounted therein, of derrick legs apertured to receive the removable pintles for pivotal support from the body, said legs being provided above said pintles with a pivotally mounted clamp having spaced fingers, a pivot bar mountable upon said body and receivable between said fingers when said legs are in upright position to register the fingers with the pivot bar, one of the fingers being engageable with the pivot bar upon approaching the latter pivotally to swing the clamp to cause the other finger to engage the bar in a locking position, and a keeper for retaining the finger in locking position with the bar, the bar and fingers providing fulcrum means for erection and dismantling of the derrick legs.

2. The combination with a vehicle body com-

prising a bed and side walls, of bracket fittings connected with the side walls near the rear of the latter, a substantially horizontal bar mountable on said bracket fittings, a derrick having intermediate its height a bracket pivotally mounted thereon and formed with spaced projecting fingers between which the bar is receivable, said bracket being pivotally moved upon engagement of one of the fingers with the bar to clamp the opposed finger in locking position about the bar, and removable keeper means automatically actuated to retain the finger in locking position on the bar, and means for holding the lower end of the derrick in detachable pivotal connection with the vehicle body.

3. A derrick, adapted for operation from a truck body, having two relatively adjustable connected legs adapted to rest on the body in juxtaposed position, a fulcrum bar removably mounted upon the truck body and over which the connected legs are tiltatable, means for pivotally and removably securing the legs to the truck body below the bar, means for removably securing the legs to the bar for tilting movement thereover including jaws pivotally mounted upon the respective legs and movable into engaging position with the fulcrum bar upon contact with the latter, and automatically-actuated means for holding the jaws in engaging position, a drum in the truck body and a boom line tracking thereover, the line being secured to the legs above the fulcrum bar, a second drum in the truck body and a load line tracking thereover, means for operating the drums, and sheaves over which the load line traverses mounted on one of said legs above and below the fulcrum bar.

4. A derrick, for use upon a support, the derrick having a main leg, a bracing leg secured adjacent its upper end to the upper end of the main leg and diverging therefrom toward its opposite end, releasable means for pivotally securing the lower ends of the legs to the support, a fulcrum bar mounted on the support intermediate the ends of the legs, automatically clamping means mounted on the legs for securing intermediate parts of the respective legs to the fulcrum bar for swinging movement thereover including pivotally-mounted jaws engaged by the fulcrum bar and movable into engaging position with the fulcrum bar upon contact with the latter, automatically-actuated means for holding the jaws in engaging position, the derrick having a boom line connected thereto and sheaves mounted thereon above and below said automatically clamping means, a load line traversing the sheaves, and a winch including drums mounted on the support for the boom and load lines.
